HINGE

Harold E. Van Voorhees, Detroit, Mich., assignor to The Atwood Vacuum Machine Company, a co-partnership composed of Seth B. Atwood and James T. Atwood, Rockford, Ill.

Application May 12, 1937, Serial No. 142,096

5 Claims. (Cl. 16—135)

This invention relates to a new and improved concealed hinge for the doors of motor vehicles, and is more particularly concerned with improvements on the ball-and-socket type concealed hinge disclosed in my earlier application Serial No. 128,356, filed March 1, 1937.

One of the principal objects of the present invention is to provide a hinge of the kind mentioned of simpler and more economical construction, and one which at the same time is stronger and more rigid and easier to install.

Another object is to provide a hinge having the socket member thereof of stamped sheet metal construction and designed so as to use a minimum amount of material for low cost, while at the same time incorporating outwardly bent flanges around the slotted portions to obtain the desired strength and rigidity.

The invention is illustrated in the accompanying drawing, wherein

Figure 1 is a partial side view of an automobile, the doors of which are equipped with concealed hinges made in accordance with my invention;

Fig. 2 is a vertical section on the line 2—2 of Fig. 1, on a larger scale, showing an end elevation of the hinge;

Fig. 3 is a cross-section on the line 3—3 of Fig. 2, looking at the back of the hinge, and

Fig. 4 is a horizontal section on the line 4—4 of Fig. 3.

The same reference numerals are applied to corresponding parts throughout the views.

Referring first to Figs. 2 to 4, and mainly Fig. 4, 5 designates the pillar and 6 the door, but it will soon be evident that it is immaterial whether the socket member 7 and gooseneck member 8 of my improved ball-and-socket hinge are mounted on the pillar and door, respectively, or vice versa. The gooseneck member 8 comprises an L-shaped neck or shank 9 terminating at one end in a ball head 10, and having the other end reduced and formed to oblong cross-section, as indicated at 11, and entered in a correspondingly shaped hole 12 in a plate 13, the reduced end 11 being either upset or welded at its extremity 14 to secure the parts together. Horizontal slots 15 in the plate 13 receive bolts 16 which thread in holes in a tapping plate 17 welded or otherwise suitably secured to the inside of an indented portion 18 on the edge of the door 6. The outside of this indented portion provides a flat seat 19 for engagement by the plate 13. The neck or shank 9 of the gooseneck member operates with ample clearance in a horizontal slot 20 in one side wall of the inner

channel-shaped member 21 of the pillar 5. The web 22 of this channel-shaped member provides a seat for the socket member 7, a portion of the web being embossed, as at 23, to provide a recess in the hinge seat for the socket 24. The socket member 7 comprises simply two plates 25 and 26 formed at the centers to provide half of the socket 24 in the plate 25 and the other half in the plate 26. Registering horizontal slots 27 in the plates 25 and 26 have bolts 28 entered therein for fastening the socket member 7 to the pillar, the bolts being passed through holes in the web 22 and threaded in nuts 29, welded or otherwise suitably secured on the opposite face of the web. The plates 25 and 26 forming the socket member 7 are held together by rivets 30 located around the socket 24. The plate 25 is cut away on one side of the socket, as at 31, and the plate 26 has a slot 32 formed therein in register with the opening 31 to provide working clearance for the neck or shank 9 on the socket member 7, sufficient to allow the door 6 to swing open to a position approximately at right angles to the body 5. The sheet metal alongside the slot 32 is bent outwardly to provide a reinforcing flange 33 extending the full length of the slot.

In regard to the mounting of the doors, it must first be understood that the tapping plates 17 and nuts 29 are so accurately located on the doors and pillars that the hinged edges of the doors will be hung at the right elevation in the door openings, or near enough for practical purposes. Shims 34—37 are entered in the door opening around the door, as illustrated in Fig. 1, when the two hinges, indicated at A and B, have been loosely secured in place; that is to say, with the bolts 16 and 28 threaded in place loosely enough to allow the gooseneck and socket members to shift horizontally relative to the hinge seats. These shims are usually wedge shaped and are adjusted by a workman inside the car, until the door has been wedged in approximately the desired position, centrally located in the door opening and properly lined up with the body and the other door 6'. The latter has its pair of hinges A' and B' and will be shimmed in a similar manner, although no shims are indicated on Fig. 1. In view of the fact that the hinge seats 19 on the door are in a plane at right angles to the hinge seats 22 on the body, and the gooseneck members 8 are adjustable in and out on the seats 19 and the socket members 7 are adjustable back and forth on the seats 22, it is clear that all of the necessary adjustments

are provided. To begin with, while the bolts 28 are loose, the socket members 1 are free to slide back and forth on the seats 22, and when the door has been properly adjusted, as just described, the bolts 28 can be tightened from inside the body through the openings 38 in the cross piece or filler 39 forming the inner wall of the channel member 21 of the door pillar. In a similar manner, while the bolts 16 are loose, so that the gooseneck members 8 are slideable in and out on the seats 19, it is clear that the door can be adjusted in the manner described, and when properly adjusted can be held in fixed relation to the hinges by the tightening of the bolts 16. The first tightening of these bolts, sufficient to maintain the adjustment, can be accomplished with an end wrench from inside the body before the door is opened and the shims removed. Care will be taken in the opening of the doors not to cause the hinge members to shift in relation to the doors and pillars, and when the doors are opened, all of the bolts 16 can, of course, be tightened up. Then the doors can be closed again to recheck their adjustment, and, while I have not shown dowels for permanently locating the hinge members with respect to the doors and body, it should be understood that these may be provided in a similar manner as disclosed in the copending application of Seth B. Atwood, Serial No. 135,068, filed April 5, 1937, namely, by simply providing holes in the plates 13, 25 and 26, and drilling holes in the hinge seats in register with these holes after the doors have been properly adjusted, and driving steel dowel pins into the registering holes to prevent shifting of the parts from adjusted positions.

It should be clear from this description that I have provided a concealed ball-and-socket hinge for the doors of motor vehicles of an extremely practical and commercially feasible design and construction, inasmuch as it can be produced at a low enough cost to be competitive with the old style pintle hinges, and its design is such that it lends itself to easy assembling on the doors and pillars of cars of present-day construction. It is obvious that the ball heads 10 swivelled in their sockets 24 each determines a single point of suspension, and these two points thus fixed determine the hinging axis of the doors in a plane 50 inwardly spaced from the curved outside surfaces of the door and body portions. As a result, the doors swing uniformly smoothly throughout their range of opening, and since the sockets are just inside the outer wall of the pillars next to the 55 joint line between the doors and pillars, the hinge axes are properly located for a large enough range of door movement and give ample clearance between the doors and the curved outside of the body. The fact that the hinges are not bent in 60 any way to make the doors fit, as was previously the practice with pintle hinges, eliminates the likelihood of the hinges being placed under any stress and there is accordingly no binding whatever and no danger of play developing and giving 65 rise to door rattling, it being generally conceded that with the old style pintle hinges, most of the wear and consequent door rattle was due to misalignment resulting from the bending of the hinges in the mounting of the doors. Furthermore, these ball-and-socket hinges afford a much 70 lower unit bearing pressure than the old style pintle hinges, so that wear is greatly reduced and longer life assured.

76 It is believed the foregoing description conveys a good understanding of the objects and ad-

vantages of my invention. The appended claims have been drawn with a view to covering all legitimate modifications and adaptations.

I claim:

1. As an article of manufacture, a socket member for a ball-and-socket hinge comprising two flat sheet metal plates having a socket to receive the ball member therebetween, said socket formed partly by a substantially hemispherical recessed portion intermediate the ends of one plate and partly by another substantially hemispherical recessed portion in and intermediate the ends of the other plate registering therewith, the one recessed portion having an elongated opening provided in the wall thereof for extension therethrough of a neck on the ball and oscillation through substantially 90° , the opposed end portions of said plates constituting attaching portions and having means for securing the same together so as to confine the ball of the ball member in place in the socket for oscillatory movement, the plate with the recessed portion having the elongated opening provided in the wall thereof being formed to provide a continuous outwardly projecting flange defining the opening and serving to reinforce the plate at that portion. 25

2. As an article of manufacture, a socket member for a ball-and-socket hinge comprising two flat sheet metal plates having a socket to receive the ball member therebetween, said socket formed partly by a substantially hemispherical recessed portion intermediate the ends of one plate and partly by another substantially hemispherical recessed portion in and intermediate the ends of the other plate registering therewith, the opposed end portions of said plates constituting attaching portions and having means for securing the same together so as to confine the ball of the ball member in place in the socket for oscillatory movement, the one recessed portion having an elongated opening provided in the wall thereof transversely with respect to said plate and extending from one edge of the plate inwardly to the recessed portion for extension therethrough of a neck on the ball and oscillation through nearly 90° , and the other recessed portion having a registering elongated opening provided therein also extending from the edge of the plate inwardly to the recessed portion to permit an increased range of oscillatory movement through 90° , the plate with the first-mentioned recessed portion having the elongated opening provided therein being formed to provide a continuous U-shaped flange extending inwardly along one side of the opening and around the inner end of the opening on the recessed portion and outwardly along the other side of the opening, said flange projecting outwardly from the plane of the plate. 30 35 40 45 50 55

3. A hinge comprising cooperating ball-and-socket members, the ball member comprising a ball head and a goose-neck extending therefrom and adapted to be attached at its remote end to one of two relatively hinged parts; the socket member being adapted to be secured to the other of two relatively hinged parts and comprising two elongated sheet metal plates, one having a transverse slot provided therein intermediate the ends thereof extending from one edge inwardly and communicating with one side of a substantially semi-spherical socket portion projecting out of the plane of the sheet metal of said plate, and the other plate having a transverse slot provided therein in register with the first slot extending from the edge of the second plate inwardly and ..

communicating with one side of another substantially semi-spherical socket portion projecting out of the plane of the sheet metal of the second plate in register with the first-named semi-spherical socket portion, the slot in the second plate being extended along the wall of the socket portion far enough to provide clearance therein for the gooseneck of the ball member throughout a range of approximately 90° of swinging movement of the ball member relative to the socket member, said second plate having a continuous U-shaped flange extending inwardly along one side of the transverse slot and around the inner end of the slot on the socket portion and outwardly along the other side of the transverse slot, 15 the flange projecting outwardly from the plane of the plate.

4. A hinge for the door of a motor vehicle, comprising an angular gooseneck adapted to be secured to the edge portion of the door so as to project therefrom substantially horizontally, said gooseneck terminating in a ball head, and a socket for reception of the ball head comprising two flat sheet metal plates adapted to be fastened in abutment with one another in a vertical plane to a vertical wall of a pillar on a motor vehicle body with the ball head confined for pivotal movement in a socket provided between said plates, said socket being formed half by a hollow sub-

stantially semi-spherical portion protruding from the plane of one of said plates and formed from the sheet metal thereof and half by another opposed hollow substantially semi-spherical portion protruding from the plane of the other of said plates and formed from the sheet metal thereof in registering relation with the first-mentioned semi-spherical portion, the ball head having a swivel fit in said socket, and the wall of at least one of said semi-spherical portions having an elongated horizontal slot provided therein through which the gooseneck extends for swinging movement relative to the socket through substantially 90° in the opening and closing movements of the door, said slot being extended from the socket to the adjacent edge of the plate, and said plate being formed to provide a continuous outwardly projecting flange defining the slot and serving to reinforce the plate at the slotted portion.

5. A hinge as set forth in claim 4, wherein the other plate also has an elongated opening provided therein in register with said slot, the opening extending from the edge of said plate inwardly to the semi-spherical socket portion thereof so as to provide an increased range of swinging movement for the gooseneck.
